UNITED STATES PATENT OFFICE

PETER C. BRUCKMANN, OF ST. LOUIS, MISSOURI, ASSIGNOR, BY MESNE ASSIGNMENTS,
TO VORCLONE COMPANY, A CORPORATION OF WISCONSIN

POSITIONING DEVICE FOR LAUNDRY MACHINES

Application filed June 20, 1924. Serial No. 721,279.

This invention pertains to safety devices and particularly such as may be applied to apparatus in which a heavy power driven member must at certain times be moved by hand 5 so as to position the same.

In certain types of machinery, as for instance in laundry machines, in which the laundry tub is power driven during the normal operation, the power driven element, in 10 this case the drum, must be stopped in a certain position so that the door of the drum will stand opposite the opening for the insertion or removal of the clothes. The stopping of 15 the power drive is usually not arranged to stop the drum in any particular position and consequently the drum must be moved by hand to its proper position after the power drive has been stopped.

Various devices have been applied for thus 20 positioning the drum. These usually involve a hand driving element which may be engaged or disengaged from the drum. If the hand driving device is not specially protected there is danger that it may be thrown into engagement 25 accidentally while the power drive is active. As the hand operating device is usually provided with a crank for operating the same, there is danger that such accidental engagement will cause the crank to be revolved 30 by the power drive. Obviously this is a source of danger to the attendants operating the machine.

One of the objects of this invention therefore is to provide means for positioning such 35 a power driven element by hand which is amply protected against accidental operation.

Another object is to provide such a hand 40 positioning device so arranged that the operator must positively throw it into engagement by manual manipulation in order to operate the same. Another object is to provide such a device which will automatically return to a free or disengaged condition as soon as the 45 operator releases his grasp.

Further objects will appear from the following description taken in connection with the accompanying drawing, in which:

Figure 1 is a plan view of the end of the 50 power driven laundry tub showing a device

embodiment this invention in connection therewith.

Figure 2 is an enlarged detail sectional view taken on line 2—2 of Figure 3.

Figure 3 is a section on line 3—3 of Figure 55 2; and

Figure 4 is an enlarged section on line 4—4 of Figure 1.

The invention is illustrated in the drawing as applied to a laundry tub 1 within which the 60 clothes drum 38 rotates on a shaft 2. A gear 3 on the shaft is provided for driving the drum. The power connections which drive the drum during normal operation may include a pair of loose pulleys 39, and a tight 65 pulley 40 on a countershaft 41 carrying a pinion 42 which engages the gear 3. A shifter 43 is adapted to shift an open belt 44 or a cross belt 45 to the tight pulley 40 to drive the drum in opposite directions. These connections are well known in the art.

Mounted on the end of the tub 1 and adjacent the periphery of the gear 3 is a supporting bracket 4 in which are mounted a pair of short shafts 5 and 6. Slidably mounted on the 75 shaft 5 is a pinion 7 whose hub 8 has formed thereon a clutch member 11 and a sleeve 10. The clutch member 11 is provided on its periphery with a series of teeth as illustrated in Figure 4. Loosely mounted on the sleeve 10 and adjacent the clutch member 11 is a crank 80 arm 12. The arm 12 is loose on the sleeve 10 and is retained in place thereon by a nut 13 engaging threads on the sleeve.

Pivoted at 14 on the arm 12 is a locking 85 member or dog 15. The dog 15 is provided with teeth 16 symmetrically disposed on opposite sides of the center line joining the pivot 14 and center of the shaft 5. The teeth 16 are positioned so that when the dog 15 is 90 rocked about its pivot 14 one or the other of these teeth will engage the teeth of the clutch member so as to lock the same to the crank arm 12 so that the clutch member and therefore its connected pinion 7 may be driven by 95 the crank arm. The dog 15 is formed with a pair of curved cam portions 17 symmetrically disposed on opposite of a V-shaped extension 18, as illustrated in Figure 4.

Mounted on the arm 12 and adjacent the 100

dog 15 is a guide 19 provided with a central aperture 20 within which is housed a spring 21 acting on a ball 22 which is positioned to engage the extension 18 of the dog. The arrangement is such that when the dog is in central or neutral position, the ball 22 will rest upon the top of the extension 18 which is slightly flattened at its top for that purpose. When the dog is rocked on its pivot to either side, the ball 22 will drop into the depression between the extension 18 and one of the cam portions 17 so as to provide a latch to hold the dog in position. Also guided in the guide member 19 is a pair of thrust rods 23. These rods may be formed of a stout wire which is bent laterally above the guide 19 so as to provide shoulders 24 and then extends upwardly along the arm 12 to the operating end thereof where it is pivoted at 25 to a lever 26 which will be more particularly described hereinafter. A spring 27 surrounds the wires 23, bearing at one end against the guide member 28 and at its lower end against the shoulders 24. This spring operates to urge the thrust rods 23 downwardly, as in Figure 4, so that their ends will bear against the cam portions 17 of the dog. When the dog 15 is rocked to one side and latched by the ball 22, one or the other of the cam portions 17 will be lifted or moved nearer to the guide 19. If when the dog is in this position the thrust rods 23 be released to move under the action of this spring 27, one of these rods will engage the lifted cam 17 and force the same back to neutral position or until both rods 23 rest on their respective cams 17. The thrust rods 23 therefore provide means for returning the dog to its neutral position. When the dog is returned to neutral position, the ball 22 will again rise to the top of extension 18. The operating end of the crank arm 12 is provided with a grip 29. This grip is recessed so as to receive a lever 26 when pressed inwardly by being included within the grasp of the operator. Lever 26 passes through a notch 30 in the end of the arm 12 and is pivoted at 31 to said arm. The short end of the lever is pivoted at 25 to the thrust rods 23 as previously described. It would be clear therefore that so long as the lever 26 is included within the operator's grasp of the grip 29, the thrust rods 23 will be held clear of the dog 15. When in this condition the dog may be rocked by hand to either one side or the other so as to engage the clutch member 11 for driving the pinion 7. As soon as the operator releases his grasp, the spring 27 will operate through the thrust rods 23 to automatically return the dog to neutral position and free the arm 12 of driving engagement with the pinion 7.

The shaft 6 may be provided with a reduced portion 32 and a further reduced shank 33. Pivot on the shank 33 is a pair of interlocking dogs 34 and 35. These dogs inter-

lock with each other for pivotal movement about the shank 33 in the same manner as the blades of a pair of scissors, and are urged toward each other by a spring 36 surrounding the reduced portion 32 of the shaft 6.

The dogs 34 and 35 are provided with manipulative handles 37 for operating the same. By pressing together the handles 37, the dogs may be sprung apart and when the handles are released will spring together again under the influence of the spring 36.

When in closed position, the dogs 34 and 35 stand adjacent the pinion 7 so as to prevent the same from sliding along the shaft 5 into engagement with the gear 3. These dogs therefore provide a stop to prevent the accidental engagement of this pinion with the gear. When it is desired to move the drum by hand, the operator by pressing together the handles 37 may move the dogs out of the path of the pinion 7 which may then be slid along the shaft 5 into engagement with the gear 3. When the pinion is in this position, the dogs 34 and 35, when released, will fall into engagement with the teeth of said pinion. Since there are two dogs the pinion will be locked against rotation in either direction. If, however, one or the other of these dogs be moved out of engagement with the teeth of the pinion by operating the handle 37, the pinion may then be operated in one direction, the other dog acting as a pawl to restrain the same against reverse rotation. These dogs may therefore be operated either so as to lock the pinion absolutely or so as to act as a pawl against rotation in either one or the other direction.

The operation of the device is as follows: During the normal operation of the drum by the power drive, the device stands in the position illustrated in Figure 1 with the pinion 7 out of driving engagement and retained out of engagement by the dogs 34 and 35. There is thus no possibility of the pinion being accidentally moved into engagement while the drum is being driven. After the drum has been stopped, the operator may manipulate the handles 37 so as to clear the pinion 7 for movement into driving engagement with the gear 3. Even in this case, however, if this movement should be made before the drum actually came to rest there would be no danger to the operator since the arm 12 is at this time entirely free of the pinion 7. The pinion may therefore be rotated without danger of its swinging the crank arm with it. In order to turn the drum, the operator first grasps the grip 29, thereby depressing the lever 26 and raising the rods 23 out of engagement with the dog 15. He then manually rocks the dog 15 in one direction or the other according to the direction of rotation desired. He will then grasp one of the handles 37 so as to free the pinion 7 from rotation in one direction. Now by turning the crank arm 12, the pinion

7 will be driven to drive the gear 3 and rotate the drum. During such rotation the unreleased dog 34 or 35 will act as a pawl to prevent the weight of the clothes in the drum 5 from turning the same backward against the effort of the operator. When the drum has been properly positioned so as to bring its door 48 opposite the door 49 of the tub, the handle 37 is released and the drum is then 10 locked in that position. The operator now simply releases the grip 29, whereupon the spring 27 will return the dog 15 to neutral position and free the arm 12 from engagement with the clutch member 11, and the arm 15 will drop to a vertical position so as to be out of the way. When it is desired to resume power driven operation, it is only necessary to draw the arm 12 outwardly away from the tub and the pinion 7 will be drawn out of engagement with the gear 3 and dogs 34 and 35 20 will snap together behind said pinion so as to prevent the same from accidentally returning to engagement with the gear.

It will be seen therefore that in accordance 25 with this invention means for positioning such a heavy drum or similar member is provided which is protected against danger to the attendants. The accidental engagement of pinion 7 is prevented by a positive stop which 30 must be manipulated manually before the pinion can be engaged. The crank arm furthermore is always free of the pinion except when in the hands of the operator. Furthermore, the operator must retain his grasp of the grip 35 in order to maintain operating engagement. In fact, in order to position the drum the operator must have both hands engaged. One hand grasps the grip 29 and operates the pinion for turning the drum, while the other 40 hand holds one of the handles 37 so as to free one of the dogs 34 or 35. As soon as the operator releases the device, it returns to a condition in which either the drum is absolutely 45 locked against rotation or in which it is perfectly free to rotate without danger to any bystander.

It is obvious that various changes may be made in details of construction without departing from the spirit of this invention; it is, therefore, to be understood that this invention is not to be limited to the specific details shown and described.

Having thus described the invention, what is claimed is:

1. In a power driven laundry machine of the character described having a tub provided with a door and a drum rotatable in the tub and having a door and adapted to be selectively positioned by hand, an engageable driving element, an operating handle, a pawl on said handle adapted to effect driving engagement between said handle and said element in one direction, means for latching 60 said pawl in driving engagement, and a cen-

tering device operating upon release of said handle to disengage said pawl.

2. In a power driven laundry machine of the character described having a tub provided with a door and a drum rotatable in the tub and having a door and adapted to be selectively positioned by hand, an engageable driving element, an operating handle therefor, means normally free adapted for manual operation to effect engagement of said handle with said element, and means for locking said element adapted upon manual release to permit driving movement thereof in one direction but to prevent such movement in the reverse direction.

3. In a device of the character described, a rotatable gear, a pinion slidable into and out of mesh with said gear, and means normally preventing said pinion from sliding into mesh with said gear, said means including a lever pivotally mounted for movement into the path of said pinion, and a spring constantly urging said lever into said path.

4. In a device of the character described, a rotatable gear, a pinion slidable into and out of mesh with said gear, and means normally preventing said pinion from sliding into mesh with said gear, said means comprising a pair of dogs pivoted for movement in opposition to each other and a spring urging said dogs toward each other, said dogs being engageable with the teeth of said pinion when moved out of the path thereof.

5. In a device of the character described, the combination with a rotatable gear, a pinion slidable into mesh with said gear, and a manually disengageable dog normally in the path of said pinion and positioned radially of said gear, said dog being automatically engageable upon release with the teeth of said pinion when the latter is in mesh with said gear and including means pressing it constantly toward a position for such engagement.

6. In a device of the character described, the combination with a rotatable gear, a pinion slidable into mesh with said gear, a manually operable dog pivoted for movement into the path of said pinion and engageable with the teeth thereof when the pinion is meshing with said gear, and a spring constantly urging said dog into said path and into engagement with said teeth.

7. In a device of the character described, the combination with a rotatable gear, a pinion slidable into mesh with said gear, a manually operable dog normally in the path of said pinion and positioned radially of said gear, said dog being provided with constantly acting pressure means whereby it is automatically engageable with the teeth of said pinion when the latter is in mesh with said gear and automatically movable into the path of said pinion when the latter is out of mesh with said gear, and a handle for rotating 125

said pinion provided with means for manually connecting it with the pinion, said means being normally disengaged from the pinion.

8. In a device of the character described, the combination with a rotatable gear, a pinion slidable into mesh with said gear, a manually operable dog pivoted for movement into the path of said pinion and engageable with the teeth thereof when the pinion is meshing with the gear, a spring constantly urging said dog into said path and into engagement with said teeth, a handle connected with said pinion for rotation relative thereto, a ratchet wheel secured to said pinion, a pawl manually engageable with said wheel, and means normally maintaining said pawl disengaged and operable from said handle to release said pawl for manual operation.
20. 9. The combination with a member adapted for mechanical and manual rotation, of a manually operable rotating device requiring, as a safety measure, both hands of the operator for its manipulation, said device comprising a latch normally effective to secure said member against rotation and subject to pressure engagement requiring continued contact of the operator's hand to maintain it disengaged and an operating handle engageable with said member but normally disengaged and requiring continued contact of the operator's other hand to maintain it engaged.

10. The combination with a member adapted for mechanical and manual rotation, of a manually operable rotating device, including a handle and a detent separately controlling the movement of said device, said handle and detent being normally in positions rendering said device ineffective for the rotation of said member and constantly pressed automatically toward such positions, and sufficiently remote to make simultaneous operation impossible except in the use of both hands of the operator.

In testimony whereof I affix my signature this 5th day of May, 1924.

PETER C. BRUCKMANN.
